(57) **CLAIM**

The ornamental design for an angel pillow doll, as shown and described.

DESCRIPTION

FIG. 1 is a front elevational view of an angel pillow doll showing my new design;

FIG. 2 is a rear elevational view thereof; and,

FIG. 3 is a left side elevational view thereof, the right side being a mirror image.

The broken lines in the drawing are for illustrative purposes only and form no part of the claimed design.
